ABSTRACT: An underwater breathing device to reduce the occurrence of caisson disease (bends), oxygen poisoning, and nitrogen narcosis in divers descending or ascending in the sea. The device provides, on demand of the diver or on a bleed basis, a correctly stabilized, pressurized and proportioned combination of gases to provide for favorable underwater breathing. In the device, the carbon dioxide exhaled by a diver is mixed with a mixture of gases released and the mixture is then bubbled through ambient water to remove the carbon dioxide prior to entry into a storage tank, the contents of which are pressurized to ambient water pressure. A supply of the mixture is then passed to a breathing chamber, from the storage tank, on each demand of the diver with said storage tank supply simultaneously being replenished with the gas mixture.

UNDERWATER BREATHING DEVICE

This invention pertains to an underwater breathing device which provides a gas mixture of a specific nature, after passing the mixture through ambient water, the purpose being to provide and maintain the correct stabilization and pressurization of gases to eliminate wholly or partially caisson disease (bends), oxygen poisoning and nitrogen narcosis in man's descent into and ascent from the sea.

Bends or caisson disease has always been attributed to formation in the blood of nitrogen bubbles which act as plugs in the smaller blood vessels. However, research in recent years at various universities and hospitals has led the researchers to conclude that divers who get the bends may be injured because their blood flow slows down under rapid decompression, not because they get nitrogen bubbles in the blood.

Research in which animals were subjected to great pressures, as experienced in deep diving, and then decompressed rapidly disclosed that, after decompression, the blood flow in the smallest vessels, the capillaries, slowed down. This happened because plasma drained out through the vessel walls into the spaces between the capillaries and the cells, making the blood remaining inside the vessels thick, sludgy and slow moving. The complete absence of gas emboli (obstructions) in severe but nonlethal decompression sickness was noted.

It has been concluded by these researchers that the bends or caisson disease is caused by the lack of oxygen to the tissues that results from a reduced flow of blood and that gas embolism only occurs as a terminal result.

The foregoing parallels of thought by the various researchers forms the basis of the instant invention, one of the principal objects of which is to provide an underwater breathing device whereby a diver can mechanically calibrate the proportions of a plurality of gases flowing into the breathing device through an automatic depth compensating gas proportioner which operates basically on the pressure differential of ambient water as a diver descends or ascends. A drop in pressure in the proportioner permits ambient water pressure to actuate valves therein to automatically compensate for the drop to maintain the flow of the correctly calibrated mixture in proportion to the depth of the water.

Another object of the instant invention is to provide the proportioned gases to the diver selectively on a demand or bleed basis, demand air being provided each time the diver inhales or, if desired, adjustment can be made to provide a constant supply of proportioned gases to the diver on a regulated bleed basis.

A further object of this invention is to recirculate carbon dioxide exhaled by the user by introducing it into and mixing it with other gases and bubbling the mixture through ambient water to break the mixture into a soluble solution whereby the carbon dioxide is dissipated in the water prior to entry of the gas mixture into a storage tank to be drawn upon for breathing purposes.

Yet another object is to provide filter means at the mouth of said storage tank comprising, a diffuser filter to further break the gas bubbles into smaller particles, and a chemical filter immediately thereafter to remove any remaining impurities therefrom, to provide a favorable gas mixture for underwater breathing.

Still another object of the present invention is to utilize ambient water to pressurize the gas mixture in the storage tank to ambient water pressure.

A still further object of the instant invention is to provide a mouthpiece in open communication with a breathing chamber through which the proportioned, pressurized gases from the storage tanks are drawn each time the diver inhales.

Yet another object of this invention is to utilize ambient water pressure to actuate valve means to charge the breathing chamber, communicating with the mouthpiece, with the proportioned, pressurized gases from the storage tank when the pressure in said chamber drops below ambient water pressure due to inhaling by the diver, and to simultaneously actuate another valve means to recharge the storage tank.

In accordance with these and other objects and advantages which will become more fully apparent hereinafter, the instant invention will now be described with reference to the accompanying drawings in which:

5 FIG. 1 is a semischematic, exploded perspective view of the underwater breathing apparatus of the present invention. Referring to the drawing in which like reference numerals designate like or similar parts throughout, the numeral 10 generally indicates a plurality of gas supply hoses extending from respective pressurized gas tanks (not shown) containing various gases which, when preconditioned by being correctly proportioned and pressurized, provide for ideal underwater breathing. The gases pass through the hoses 10 into an automatic depth compensating gas proportioner 12 which will be understood fully from the following disclosure. From the proportioner 12, the gas passes through a singular hose 14 to a bleed or demand valve assembly 16. From the valve assembly 16 the proportioned gases pass through an inlet manifold 18, and a pair of transfer tubes 20 and 22 to a pair of tubular mixing chambers 24 and 26 where the preconditioned gas mixture is mixed with carbon dioxide, which has been exhaled by the user, in a manner to be subsequently described. Next, the mixture passes through one-way valves 28 and 30, in the respective gas mixing chambers, into respective air bubble release filters 32 and 34 at the lower distal ends of the mixing chambers 24 and 26. Each of the filters 32 and 34 is provided with a multiplicity of very small apertures 36 to break the gas into extremely small bubbles which are released and rise through ambient water 38 to be collected in an automatic pressurizing and storage tank 40. In effect, the pressure equalization to compensate for the depth takes place by reason of the release to the ambient water. As illustrated in the drawing, the bubble release filters are positioned beneath the open lower end of the tank 40 with said end carrying a diffuser filter 42 and a chemical filter 44 immediately thereabove for a purpose to be further described in conjunction with a detailed description of the operation of the device.

40 The pressurizing and storage tank 40 supplies ideal breathable gas to a higher or elevated breathing chamber 46, within a housing indicated generally at 48, via a one-way check valve 50, an intake and exhaust manifold 52, and an intake and exhaust valve 54. A mouthpiece 56 is attached to the outer wall 58 of the housing 48 as indicated by the broken arrowed line 60. When the diver exhales through the mouthpiece into the chamber 46, the exhaled carbon dioxide causes a build up of pressure in the chamber 46 which opens the intake and exhaust valve 54 permitting said carbon dioxide to pass into the manifold 52 where the resulting pressure build up closes the one-way check valve 50 and opens a pair of one-way check valves 62 and 64 in communication with said respective mixing chambers 24 and 26 to permit the carbon dioxide to pass therein to mingle with the gas mixture.

55 The housing 48 includes, a breathing chamber 46 defining portion 66, and a cover portion 68 provided with perforations 70. A diaphragm 72 is interposed between the housing portions 66 and 68 to separate ambient water, which enters through the perforations 70, from the chamber 46 and to actuate the bleed and demand valve assembly 16 as well as the intake and exhaust valve 54 in a manner to be described. As illustrated in the drawing, the inlet manifold 18 is positioned within the chamber 46 and includes an intake port 74 which receives one end 76 of a tilt valve 78 as indicated by the broken line 80. An adjustable valve seat member 82 is fixed to the end of the singular hose 14 and receives the gas mixture therefrom through a port 84. The member 82 also includes a convex seat 85 in communication with said port 84 to receive a companionably configured enlarged head portion 86 of the tilt valve 78. As illustrated in the drawing, the valve 78 is provided with an air passage 88 extending therethrough with its intake port 90 axially offset relative to the port 84 in a manner to provide communication between the port 84 and the manifold intake port 74 only when the valve 78 is axially tilted relative to the valve seat member 82.

The intake and exhaust valve 54 includes a stem portion 92 extending into the chamber 46 and is provided with an enlarged head 94 at its inner distal end. Both the intake manifold 18 and the intake and exhaust valve 54 are normally spring biased in any convenient manner (not shown) to valve-closed positions. When downward forces are applied thereto in a manner to be described in the following paragraph and as indicated by the force lines 100 and 102, the tilt valve 78 and the intake and exhaust valve 54 are simultaneously upset or opened to permit gases to flow therethrough. A flow of gas to the tank 40 is therefore provided via the opened tilt valve 78, the manifold 18, transfer tubes 20 and 22, the mixing chambers 24 and 26, one-way check valves 28 and 30 and filters 32 and 34, and a flow of breathable gas is provided to the breathing chamber 46 from the tank 40 via the one-way check valve 50, intake and exhaust manifold 52 and the opened intake and exhaust valve 54. The check valve 50 is adapted to open only when the pressure in the manifold 52 drops below the pressure of the gas in the tank 40.

The downward forces as illustrated by the force lines 100 and 102 may be provided either by ambient water entering the housing portion 68 through the perforations to displace the diaphragm 72 downwardly when the pressure in the breathing chamber 46 is less than that of the ambient water, as occasioned when the diver inhales or mechanically by means of a button 110 which extends inwardly through a central aperture 112 in the housing portion 68. Normally, the button is biased outwardly by means of a spring 114 and is adapted to be manually depressed against the spring forces to engage the inner distal end 116 thereof with a chafe plate 118 centrally carried by the diaphragm 72, to depress said diaphragm and thereby upset or open the respective valves 78 and 54 in the manner just described. The forces indicated by the lines 100 and 102 may be applied by any convenient mechanical connection between the diaphragm 72 and the intake manifold and valve, 18 and 54 respectively.

An emergency crossover valve system is provided in conjunction with the inlet manifold 18. As illustrated in the drawing, a housing 120 in communication with one end of the manifold 18 extends outwardly through the housing 66 to receive a push button actuated valve 122. Normally, the valve 122 is spring biased outwardly to permit the gas mixture to flow from the port 74 out through the transfer tubes 20 and 22 as described. The instant an emergency occurs necessitating immediate air, the button of the valve 122 may be manually depressed causing the inner end 123 thereof to close the manifold outlets to the transfer tubes 20 and 22, to short circuit the gas mixture into the breathing chamber 46 via the port 74 which becomes aligned with a port 125 of a passage 126 in the valve 122 and a discharge port 127 of the passage 126 which becomes aligned with a port 124 which opens into the breathing chamber 46.

As previously stated, the underwater breathing device of the present invention is adapted to correctly proportion a mixture of a plurality of gases to provide for ideal underwater breathing. This is accomplished by means of the automatic compensating gas proportioner 12 which includes a plurality of tilt valves 13, one for each gas inlet, which are operated by the pressure differential of the ambient water acting on a diaphragm 15 in the same manner as in the operation of the tilt valve 78. Therefore, a drop in line pressure on "inhale" allows the greater ambient water pressure to actuate the diaphragm 15 against the tilt valves, unseating the valves and permitting a buildup of pressure within the proportioner 12 to the ambient water pressure. The gases merge in the proportioner 12 and flow out through the singular hose 14. The gas flow from each pressurized supply tank (not shown) is controlled to proportion the flow of each gas to its respective tilt valve by the turning, in or out, of a calibrated gas flow adjustment fitting 130.

In operation, it may be necessary to first pressurize the breathing device by depressing the button 110 to deflect the diaphragm 72 which in turn depresses the manifold 18 to

supply the proportioned gas mixture to the tank 40 through the tilt valve 78, transfer tubes 20 and 22, mixing chambers 24 and 26, one-way check valves 28 and 30 and bubble release filters 32 and 34. Simultaneously, the stem 92 of the valve 54 is depressed to supply the gas mixture to the breathing chamber 46 from the tank 40 via check valve 50, intake and exhaust manifold 52 and intake and exhaust valve 54 as previously described.

Thereafter, air in tank 40, pressurized to the equilization of inside and outside pressure by the ambient water, continues to pass to the chamber 46 on demand of the user. Each time air is drawn into the lungs from the breathing chamber 46 through the mouthpiece 56, a loss of pressure within the breathing chamber 46 causes actuation of the tilt valve 78 and intake and exhaust valve 54 by means of the forces 100 and 102 created by the ambient water forces deflecting the diaphragm 72 inwardly. The exhaled carbon dioxide builds up pressure in the breathing chamber 46, thereby opening the intake and exhaust valve 54 into the manifold 52, closing valve 50, and being diverted through the one-way check valves 62 and 64 where it enters the mixing chambers 24 and 26 to merge with gas mixture gases entering through the tilt valve 78, manifold 18 and transfer tubes 20 and 22. The gas mixture and the carbon dioxide become thoroughly united with each other in the mixing chambers 24 and 26 and pass out through the check valves 28 and 30, when the tilt valve 78 is opened, and air bubble release filters 32 and 34 where the gas mixture is broken into extremely small bubbles, the gas bubbles travel through open ambient water 38, through the diffuser and chemical filters 42 and 44 and into the tank 40. The differential pressure of the water bubbles the merged gases upwardly at a vigorous rate. The diffuser filter further breaks the air bubbles into a soluble solution and the carbon dioxide is rapidly dissipated in the water. The chemical filter installed immediately after the diffuser filter facilitates the rapid absorption of any remaining foreign elements from the gas mixture before it enters the tank 40. The combination of the operation of the automatically compensated gas proportioner 12 and the filter system, both being operated by the ambient water pressure, provides a constant supply of correctly proportioned, stabilized and pressurized air to the tank 40.

The bleed and demand valve assembly 16 is made to function in a manner so as to provide demand air each time air is inhaled from the breathing chamber 46 as described, or to provide bleed air in a continuous metered amount to the mixing chambers 24 and 26. This is accomplished preferably by providing an adjustable valve seat member 82 having a range of adjustment from a demand position to a position providing a predetermined maximum amount of bleed air.

I claim:

1. An underwater breathing device comprising:
A. a plurality of gas conduits extending from respective individual pressurized sources of supply, each of said conduits to supply a specific gas of a different nature to said underwater breathing device when said device is in use by a diver beneath the surface of the water;
- B. an automatic depth compensating gas proportioner providing an interior chamber for receiving and mixing said specific gases from said plurality of conduits and including:
  1. individual valve means for each specific gas to proportion same relative to the others as it enters said chamber to form a favorable mixture for underwater breathing; and
  2. means to pressurize said gas mixture in said interior chamber to the ambient water pressure;
- C. a mixing chamber for receiving said gas mixture from said automatic depth compensating gas proportioner and carbon dioxide exhaled from the lungs of the diver;
- D. a bubble release filter at the lower end of said mixing chamber communicating with the ambient water and containing a multiplicity of very small apertures to break said gas mixture and carbon dioxide into extremely small bubbles.

- bles upon passage from said bubble release filter into the ambient water surrounding said filter;
- E. a gas pressurizing storage tank having an open lower end, and being positioned above said bubble release filter in a position to collect said gas mixture from the bubbles after the carbon dioxide has been dissipated in the ambient water, said gas mixture being automatically pressurized in said tank by said ambient water to the ambient water pressure;
- F. a housing including a breathing chamber for receiving said gas mixture from said gas pressurizing storage tank on demand of the diver and a mouthpiece in open communication with said breathing chamber, said housing being positioned above said gas pressurizing storage tank;
- G. means within said breathing chamber to repressurize said breathing chamber, to the ambient water, with the gas mixture from said gas pressurizing storage tank, after each demand of the diver and to simultaneously replenish said pressurizing storage tank with said gas mixture from said automatic depth compensating gas proportioner.
2. The device as set forth in claim 1 in which said individual valve means for each specific gas is provided with a calibrated manual adjustment means to provide for the correct proportioning of the flow of gas through each of said valve means into said automatic depth compensating gas proportioner.
3. An automatic underwater breathing device as set forth in claim 2 in which said means to pressurize the gas mixture in said interior chamber of said automatic depth compensating gas proportioner to ambient water pressure comprises, a diaphragm, forming one side wall of said interior chamber, having its outer side open to ambient water pressure and said individual valve means being positioned interior of the chamber to be actuated by inward deflection of said diaphragm by said ambient water pressure when the pressure in said interior chamber falls below the ambient water pressure.
4. An underwater breathing device as set forth in claim 3 including a bleed or demand valve means intermediate said automatic depth compensating gas proportioner and said mixing chamber, said bleed or demand valve means including a hose connection to said automatic depth compensating gas proportioner for receiving said gas mixture therethrough and providing manual adjustment means to selectively supply said gas mixture to said mixing chamber on demand of the diver or to continuously supply said gas mixture thereto on a controlled metered bleed basis.
5. An underwater breathing device as set forth in claim 1 including a diffuser filter spanning the open lower end of said automatic gas pressurizing storage tank to further break said bubbles into a soluble solution to facilitate the dissipation of the carbon dioxide therefrom.
6. An underwater breathing device as set forth in claim 5 including a chemical filter immediately above said diffuser filter to absorb any remaining foreign elements from said gas mixture.
7. An underwater breathing device as set forth in claim 4 including a pair of mixing chambers in communication with said bleed or demand valve means, each of said pair providing a bubble release filter at the lower end thereof positioned beneath said open lower end of said storage tank and containing a multiplicity of very small apertures to break said mixture of gases and carbon dioxide into extremely small bubbles upon passage into ambient water to be collected in said storage tank after the carbon dioxide has been dissipated in said ambient water.
8. An underwater breathing device as set forth in claim 7 including an inlet manifold intermediate said bleed or demand valve and said pair of mixing chambers to distribute said gas mixture thereto.
9. An underwater breathing device as set forth in claim 8 including an intake and exhaust manifold communicating between said automatic gas pressurizing storage tank and said breathing chamber, said intake and exhaust manifold provid-

- ing a first valve means, between it and said breathing chamber, responsive to ambient water pressure to open said breathing chamber to said intake and exhaust manifold when the pressure in said breathing chamber is less than ambient water pressure, and a second valve means between said intake and exhaust manifold and said automatic gas pressurizing storage tank which is responsive to ambient water pressure to open said second valve means to said automatic gas pressurizing storage tank when the pressure in said manifold is less than said ambient water pressure to permit said gas mixture in said automatic gas pressurizing storage tank to pass through said second valve means, intake and exhaust manifold, and first valve means to said breathing chamber on demand of said diver.
10. An underwater breathing device as set forth in claim 9 in which said first valve means in said intake and exhaust manifold is tiltable to an open position in response to ambient water pressure when the pressure in said breathing chamber is less than ambient water pressure and axially movable to an open position when carbon dioxide is exhaled through said mouthpiece into said breathing chamber creating a greater pressure in said breathing chamber than that existing in said intake and exhaust manifold.
11. An underwater breathing device as set forth in claim 10 including a third and fourth valve means in said intake and exhaust manifold communicating respectively with said pair of mixing chambers, said third and fourth valve means being responsive to the pressures greater than ambient water pressure, created by said exhaled carbon dioxide, to permit said carbon dioxide in said intake and exhaust manifold to pass therethrough into said mixing chambers.
12. An underwater breathing device as set forth in claim 11 in which said inlet manifold is positioned within said breathing chamber and includes an inlet port and a pair of outlet ports for supplying said gas mixture to said pair of mixing chambers from said bleed or demand valve means, said inlet port being operably connected to said bleed or demand valve to supply said gas mixture to said mixing chambers on demand of said diver.
13. An underwater breathing device as set forth in claim 12 in which said first valve means in said intake and exhaust manifold includes a stem portion extending into said breathing chamber.
14. An underwater breathing device as set forth in claim 13 in which said breathing chamber in said housing includes a diaphragm forming the enclosure for one side wall of said breathing chamber, the outer side face of said diaphragm being open to ambient water pressure which deflects said diaphragm inwardly when the pressure in said breathing chamber is less than said ambient water pressure.
15. An underwater breathing device as set forth in claim 14 in which said inlet manifold is spring biased to hold the bleed or demand valve means in a normal closed position and said first valve means in said intake and exhaust manifold is spring biased to a normal closed position.
16. An underwater breathing device as set forth in claim 15 in which said breathing chamber diaphragm is operably connected to said stem portion of said first valve means to actuate same, upon inward deflection of said diaphragm, to open said breathing chamber to said automatic gas pressurizing storage tank to repressurize said breathing chamber to ambient water pressure after each demand of the diver, said breathing chamber diaphragm similarly being operably connected to said inlet manifold which is operably connected to said bleed or demand valve to actuate said bleed or demand valve means to replenish the supply of gas mixture drawn from said automatic gas pressurizing storage tank after each demand of the diver.
17. An underwater breathing device as set forth in claim 16 including a manual pressurizing valve, operable on said breathing chamber diaphragm, to permit initial pressurization of the entire system of said underwater breathing device by a diver upon entering the water.

18. An underwater breathing device as set forth in claim 17 in which said manual pressurizing valve includes a button member having its inner end in contact with the outer side of said breathing chamber diaphragm and its outer end extending outwardly of said breathing chamber housing, said button member being normally spring biased outwardly to an "off" position and manually depressable inwardly to depress said breathing chamber diaphragm to pressurize said system.

19. An underwater breathing device as set forth in claim 8

in which said inlet manifold includes an emergency crossover valve, said valve being receivable in said inlet manifold, being normally spring biased outwardly to an "off" position, and including a head portion, extending outwardly of said breathing chamber housing, adapted to be manually depressed to shut off the flow of said gas mixture to said mixing chambers and to short circuit same directly into said breathing chamber.
